UNITED STATES PATENT OFFICE.

JOHN J. MURYN, OF MILWAUKEE, WISCONSIN.

METAL-BUILDING CONSTRUCTION.

Application filed November 30, 1925. Serial No. 72,158.

This invention relates to building structures, and more particularly to metal walls therefor.

Various attempts have heretofore been made in the construction of sheet metal walls for buildings to improve their appearance by providing a construction which will be more sightly than corrugated iron, and which will have the appearance of weather boards now universally employed in frame or wood structures. With this end in view, many attempts have been made to firmly join together adjacent edges of different sheets in such a manner as to conceal them from view, thereby protecting such joints and effectually preventing the entrance of any moisture.

The methods heretofore proposed have not been altogether successful in that external fasteners were required in securing the sheets to the frame-work so as to prevent any lateral movement therebetween, and in addition the sheets were not readily replaceable. It is to be noted that external fasteners are not attractive, nor are the sheets receiving them impervious to the effects of moisture and other natural agencies.

Further, in the metal structures heretofore designed, the intersecting walls terminating in corners were covered by stops which were not uniform in contour and design with the step-shaped walls; consequently, the structure did not present a uniform appearance throughout.

One object of the present invention is the provision of concealed joints between the adjacent sheets, thereby protecting such joints and effectually preventing the entrance of any moisture.

Another object is to provide means for securing the sheets at their joints to the frame whereby the necessity of external fasteners are avoided.

A further object is to provide corner stops having the same appearance as the walls so that the structure will present a uniform appearance throughout.

Other objects and advantages will appear from the following description of an illustrative embodiment of the present invention.

To more fully comprehend the invention, reference is directed to the accompanying drawings, wherein:—

Figure 1 is a perspective view of a portion of a house or building having sheet metal walls constructed in accordance with the

present invention, parts being broken away to disclose a means of joining the adjacent sheets together.

Figure 2 is a perspective view of a segment of an outer corner stop shown in Figure 1.

Fig. 3 is a development of the corner stop shown in Figure 2, the dotted lines designating the lines of fold.

Fig. 4 is a perspective view of a segment of an inner corner stop viewing it from a position designated by arrow A in Figure 1.

Fig. 5 is a development of the corner stop shown in Figure 4, the dotted lines designating the lines of fold.

The structure selected for illustration comprises a frame having horizontally disposed angle bars 10 of any standard or appropriate construction to which is applied metal sidings 11 constructed in accordance with the present invention. The angle bars 10 serve as supports for the frame as well as connecting means for the adjoining sheets without necessitating the use of external fasteners.

The siding 11 is constructed of metal preferably of galvanized sheet iron having a succession of uniformly inclined sides 12 and overhanging ledges 13 formed by rolling, stamping, or otherwise, so as to define a step or Z-shaped cross-section having the appearance of a number of weather boards commonly employed in frame structures.

In order to properly and rigidly secure the adjacent sheets to each other as well as to conceal the joint, the uppermost inclined side 12 of each sheet 11 is bent inwardly and downwardly as at 14 and 15 respectively, thereby forming a flange, whereas the lowermost ledge 13 of the adjacent sheet 11 terminates in an inclined portion 16 having an extended flange 17 corresponding in shape with the flange 14 supra. This flange 14 with its downwardly projecting portion 15 rests on the upper surface of the angle bar 10, and the correspondingly shaped flange 16 of the lower edge of the adjacent sheet is received thereon as apparent from Figure 1. It is to be noted that the inclined portion 16 which offsets the ledge 13 from the plane of the flange 17, conceals the joint from view, thereby protecting it and effectually preventing the entrance of any moisture or water. Perforations may be provided in the flange of each sheet to coincide with threaded or plain apertures in the angle bar

so that the sheets can be secured to each other and simultaneously anchored to the frame of the structure with any suitable fasteners, such as the screws 18. It will be noted that the fasteners employed for this purpose are placed in position from the inside of the structure, and therefore the necessity of external fasteners which are subjected to the weather is entirely eliminated. The fact that the sheets are secured to the frame at their juncture stiffens them considerably without resorting to the usual practice of nailing or otherwise securing the sheets thereon from the outside which not only is undesirable, but unsightly and expensive as well.

The angles and meeting edges of the sections are covered in this instance with the corner stops 19 of step shape form similar to and in harmony with the siding associated therewith, so as to present an inexpensive and simple structure without destroying the continuity of the general design.

In this instance the corner stops 19 are formed from a strip of sheet metal of suitable dimensions, a portion of which to the left of the longitudinal center is perforated at spaced intervals corresponding to one segment, to define a triangular opening 19'. The base 20 of the triangular opening 19' coincides with the longitudinal axis 21 upon which the section is longitudinally bent. However, prior to longitudinal folding, an incision 22 equal to the altitude of the triangular opening 19' and extending in line therewith normal to the base 20, is made so that the two triangular flaps 23 and 24, corresponding in size and shape to the opening 19', can be folded inwardly about the lines 25 and 26 respectively. It will be observed that angle 20' of the triangular opening 19' determines the slope of the successive inclined sides 19, and in view thereof it is a very simple matter to construct the corner stops to conform exactly with the siding to which it is attached.

The opposite edges 27 and 28 of each segment 19 are struck outwardly and inwardly about lines 29 and 30 respectively, to form the parallel horizontal ledges 31 and 32 which are perforated at spaced points as at 33. The strip consisting of a succession of inclined faces defining Z-shaped segments is then longitudinally bent about its center axis 21 to form the angular step-shape corner stops to conform in design and appearance to the similarly shaped metal siding 11 described above. It will be noted that the longitudinal bending can be readily accomplished with little effort, in that the metal 34 constituting the connecting material between each section, is comparatively small yet adequate to sustain the segments in an integral relation. To make the corner stops water and weather tight, solder

or any other suitable material having adhesive characteristics, is applied to the flaps 23 and 24, thereby rendering the corner covering means a rigid unitary structure, of any desired length.

The perforations 33 in the horizontal flanges 31 and 32 afford means of securing the corner covering strips to the siding covered thereby without necessitating the use of any securing means on the external surfaces. This feature is highly desirable, since the water which collects about the screws or other fastening means, will drop off rather than accumulate into a mass which finds its way through the openings in which the fasteners are seated. Obviously other methods of securing the corner stops to the siding may be resorted to for the above disclosed method is only a preferred embodiment selected primarily for illustrative purposes.

The form of corner stop described above is only applicable to external corners, and since structures often are provided with walls extending outwardly from the main portion as illustrated in Figure 1, the junction of such two walls, requires a covering or stop of a form similar to that shown in Figures 4 and 5. The segment 35 shown in Figure 4 viewed from a position designated by arrow A (Figure 1) comprises a strip of sheet material which is slit for the most part along the central longitudinal axis 36 except at 37 and 38 (Figure 5) which portions serve as connecting means between the two sections. An incision 39 extending normal to the slotted longitudinal central portion 36 defines a triangular flap 40 therewith which is folded over along line 42. The opposite parallel edges 43 and 44 are then struck inwardly and outwardly along lines 45 and 46 respectively to form parallel horizontal ledges 47 and 48. The sections of the sheet are then bent longitudinally about 37 and 38 until they lie normal to each other, so as to present a corner with a sloping edge 42. As in the above described outer corner, perforations 49 may be provided in the horizontal flanges for the purpose above specified, and solder or other adhesives may be applied to the flaps in order to render the corners water-tight. The slope of the inclined sides in this instance is equal to and dependent upon the angle defined by the line of fold 42 and the longitudinal axial line 36.

It is obvious that the width of the corner covering means is quite immaterial and that it may be so extended in width as to actually constitute a partial side covering. The corner covering means may also be stamped, pressed, forged or otherwise shaped into the desired form. In fact various changes may be made in the embodiment of the invention hereinabove specifically described,

without departing from or sacrificing any of the advantages of the invention as defined in the appended claims.

I claim:

- 5 1. In a building construction, the combination with a frame, of sheets crimped to represent weather board strips having a Z-shaped cross-section, the adjacent edges of each sheet bent inwardly and downwardly
- 10 to form cooperating flanges adapted to be supported by and secured to an angle bar constituting a portion of the frame so as to provide a concealed joint, and corner stops shaped similarly to the sheets comprising
- 15 the siding and secured thereto to present a closure therefor.
- 20 2. In a building construction, the combination with a frame and angle bars constituting parts thereof, of metal siding therefor concealed securing means effective to connect the adjacent edges of said siding to each other and to said angle bars so as to present concealed joints between said sheets, and corner covering means identical in design
- 25 with the siding and secured thereto to present a structure of uniform design throughout.
- 30 3. In a building construction, the combination of metal sheets formed to present the appearance of weatherboards, and means comprising inwardly projecting flanges on adjacent edges of said sheets, said means adapted to be internally secured to bars constituting a frame therefor.
- 35 4. In a building construction, the combination of metal sheets formed to present the appearance of weatherboards, and concealed connecting means between adjacent sheets to internally secure them to a frame at their juncture.
- 40 5. In a building construction, siding comprising sheets of step-shape cross-section, correspondingly shaped corner covering means including a strip, the central portion of said strip being perforated at spaced intervals to provide polygonal openings and

similarly shaped flaps thereby adapting the strip to be bent about its longitudinal mid-portion to present a corner stop having a succession of inclined sides adapted to lie flush with said siding.

6. A method of forming step-shaped corner stops from a strip of sheet metal consisting of perforating the central portion of said strip at spaced intervals to present polygonal openings and flaps, bending the strip transversely at spaced intervals to define stepped faces, and bending the strip along its longitudinal axis to close said openings and to present angularly related sides.

7. In a metal building structure the combination of side covering means comprising horizontally corrugated sheet metal siding, and sheet metal corner covering means applied in face to face contact with said siding throughout a plurality of said corrugations to form a tight closure, said corner covering means comprising connected angularly disposed upright portions each corrugated to match each other and to match said corrugations of said siding.

8. In a metal building structure the combination of a frame including horizontal bars, and horizontally corrugated metal sheets applied to said frame in overlapping relation, the contiguous portions of said sheets having similarly formed coacting flanges extended inwardly and applied to said bars to provide a concealed anchorage for said sheets.

9. In a building structure having externally corrugated side walls, a corner closure therefor comprising a sheet metal structure having connected upright portions angularly disposed to fit the corner and extended over several corrugations of said side wall, each portion being corrugated to match said corrugations and to make face to face contact therewith throughout said corrugations.

In witness whereof, I hereunto subscribe my name this 24th day of November, 1925.

JOHN J. MURYN.
